UNITED STATES PATENT OFFICE

2,445,259

TWIN-COOLED RADIO TUBE

Abraham Binneweg, Jr., Oakland, Calif.

Application November 11, 1942, Serial No. 465,207

15 Claims. (Cl. 250—27.5)

1

My invention relates to improvements in radio tubes and the object of my improvement is to provide a radio unit adapted to ultra-high-frequency use and fitted with hollow water-cooled plate elements. Further objects are to provide a radio unit having two adjacent compartments, one with a set of flat elements, the other with a set of cylindrical elements and both water-cooled. Another object is to provide a water cooling circuit which flows in series through both the hollow plate elements. I also provide capacities near the plates for tuning adjustment, and a special spray for cooling the top of the vacuum chamber.

Figure I is a vertical section of the radio unit,

Figure II a top view—cover removed, and Figure III a perspective of the cylindrical plate element.

The unit is encased by dielectric walls 1, cover 2, and base 3, held in airtight contact by means of gaskets 4, and screws or bolts 5. Within the cover 2 are an air cooled chamber 6 and a water cooled chamber 7 with a separate cover 8.

Within the casing is a compartment 9 containing a flat cathode 10, flat grids 11, and a flat, hollow plate 12; and a second compartment 13 containing a horizontally disposed, cylindrical cathode 14 with filaments 15, a helical grid 16 supported by horizontal wires 17, and a hollow plate element with inner wall 18, outer wall 19, and flat rings 20 welded at each end to hold them in spaced relation. Tubes 21 provide entrance and exit to the hollow plate. The flat element 12 is hollow and similarly constructed.

The water cooling system comprises an intake 22, waterways 23 in the walls, hollow plate elements 12 and 24, tubes 21, external tube 32, spray 23, chamber 7 and outlet 28.

Water, air, or other cooling fluid is forced into the tube at intake 22 under considerable pressure and consequently divides and passes through several channels before merging again at the outlet 28. Some goes up through the hollow walls 23, some passes along the floor of the tube to cool the bottom, and some passes through the hollow anodes 12 and 24, as it is forced from one side of the tube to the other. Grids also may be of similar hollow construction. Then the fluid is collected in the tube 32 and forced from its perforated end as a spray to cool the top of the cylindrical tube 13, before final discharge through orifice 28. Thus all parts of the tube are cooled by the fluid stream.

The metal inserts 25 have two purposes: first, they may be used in delicate tuning, due to a capacitative effect upon the tube anodes near

which they are located, but from which most of them are insulated. Connecting different numbers of them in parallel will affect the capacities of the anodes. Secondly, the inserts 25 act as supplementary cooling agencies for conducting heat from the interior of the tube to the outside, directly, or through their conductors 29. In themselves the ceramic walls of the tube are poor heat conductors; the inserts serve to remedy this limitation.

Metal inserts 25 and conductors 29 may be used for electric connection to the elements within the tube or for capacity effect in tuning the tube. Exhaust tube 26 may also be used for electric connection. Lateral conductors 27 embedded or sealed in the walls of the casing 1, also provide electric communication with the elements within the tube. Corrugations, depressions, or pointed supports of dielectric or of conductor, 30 on the inner walls of the chambers provide a support for the elements resting against them. This support extends substantially over the entire plate surface. The grids can also be held at the sides.

The unit may be opened, elements replaced, and a new top put back on. The cathode may be activated on one side, and may contain a ceramic filler to support the elements. A hairpin or other type filament could be used instead of a cathode. The elements and case of the tube can be of any desired material.

Metal inserts 25 may contact the desired element or the elements or may contact more than one element. These inserts can also be separated from the element or elements by any dielectric so realizing either direct contact or providing for capacitative coupling to external apparatus. Screws may pass from the inserts to the outside, or the inserts can be so arranged that leads can be soldered to them at the outside of the case. If a hollow wall is used, there may be inserts in both walls as shown in Fig. 1. Each plate could have separate water or gas supply, the intake and outlets being arranged in the case at desired positions. Any number of leads to the elements could be arranged to properly support them from the sides of the case if desired. The grid and plate elements could be simple without the hollow interior which is air tight.

The cooling chamber 23 could be omitted, the outside of the case in any construction being grooved or otherwise arranged for air cooling.

Base 3 could be made wider and have hollow inserts for vertical screws which hold the case in place. Any side ears could be molded as part of

the case or of the top for holding the case in place in the apparatus.

Two circular element tubes could be in the same case; two flat element tubes could be in the same case; or one tube of each kind could be arranged in the case as in Fig. 1. Here, the elements are horizontal, but one or more of the tubes could be vertically arranged. Any number of tubes having elements of each one of them the same, or having different elements in each tube, could be arranged in one large dielectric block as in Fig. 1, having space between each of the tubes as may be needed. Elements can be of any desired shape or area.

Rigidity is one of the main features of this invention with plate supported all around, and either the elements, or the leads to them, rigidly held in the walls of the case, as in grooves. Soldering lug inserts could be used for cathodes and grids. Leads and tubes can be soldered to the plates.

The double tube here provides in one unit for any type of oscillator and for very high frequencies.

Fig. III could be arranged with welded hollow cross tubes, 31, to provide a flat or circular grid also internally fluid cooled, should this be desired, in an oscillator circuit carrying a heavy grid-plate oscillating current.

Within the scope of this invention is an openable case tube having within its single inner chamber, provision for, such as grooves, inserts, and corrugations, such that the same tube case could be changed from a flat element tube to a circular element tube.

I claim:

1. A radio unit having a main compartment, a cover for said compartment, cathode, grid and plate elements within said compartment, a chamber within said plate element, waterways in the walls of said compartment communicating with said chamber, a water compartment in the cover of said main compartment, a pipe connecting said waterways with said cover compartment and entering said compartment, and orifices near the end of said pipe.

2. A radio unit having a case, cathode and grid elements athwart said case, a corrugated inner surface for said case, a plate element adjacent said corrugations and supported thereby, metal bodies embedded in the walls of said case near said plate element for capacity effects and conductors leading from said metal bodies to the outside of said case.

3. A radio tube having a dielectric double-walled cup-shape receptacle; a hollow, cylindrical, double-walled anode within said receptacle; ways on opposite sides of said anode connecting the chamber within the walls of said receptacle to the chamber within the walls of said hollow anode for the flow of fluid; a cylindrical grid within said anode and spaced therefrom; and a cylindrical cathode within said grid, spaced therefrom.

4. A radio tube having a dielectric casing, metal inserts in the bottom of said casing, a flat plate element against said metal inserts, a plurality of grids in spaced relation to each other and to said plate, and a cathode in spaced relation to the upper of said grids, a cover on said casing having an exhaust tube therein; said cover closing the casing airtight.

5. A radio tube as in claim 4, in that the plate element is hollow for the passage of a fluid therethrough, and the inlet and outlet to said hollow

plate both extend through the dielectric walls of the case.

6. A radio tube having a dielectric casing, having a cylindrical chamber, the walls of which have metal inserts covering its surface, said inserts being in spaced relation to each other in the dielectric of the case walls, a cylindrical plate in said casing having its outer surface in contact with said inserts, a plurality of cylindrical grids in spaced relation to each other and to the cylindrical plate, and a cathode centrally located within the cylindrical plate and in spaced relation to said grids, a cover closing one side of the case airtight.

7. A radio tube as in claim 6 in which said cylindrical plate is hollow and means for passing a fluid therethrough.

8. A radio tube having an inner dielectric case, cathode and grid electrodes athwart said case, an anode adjacent the bottom of said case, an outer dielectric wall partially surrounding said inner case, a space between said case and said wall for the circulation of cooling fluid, a metal insert in the wall of said inner case, metal inserts in said outer wall, and a conductor of heat and electricity connecting said insert of the inner case with one of said inserts in said outer wall.

9. A compact radio unit comprising an outer casing, a two-compartment inner casing, a waterway between the two casings for the circulation of cooling fluid; flat cathode, grid, and anode electrodes within one of said compartments of the inner casing for high frequency operation; cylindrical cathode, grid, and anode electrodes within the other of said compartments for lower frequency operation, both of said electrode sets combining to form a complete high-low frequency unit.

10. A radio unit having compartments, covers for said compartments, cathode, grid and anode electrodes within said compartments, chambers within said anode electrodes, fluid spaces within said covers, waterways in the walls of said compartments communicating with said anode chambers, external cooling pipes connecting said waterways with the fluid spaces of said covers, and intake and outlet orifices for said waterways.

11. A radio unit comprising an outer casing, two envelopes within said casing; cathode, grid and anode electrodes for high frequency operation within one of said envelopes; cathode, grid, and anode electrodes within the other of said envelopes for low frequency operation, said anodes being of hollow construction; and a fluid chamber within said outer casing largely surrounding both of said envelopes and having passageways connecting with the hollow interiors of said cathodes.

12. A radio tube as in claim 3 having in addition corrugations upon the inner wall of said receptacle.

13. A radio unit as in claim 9 having in addition corrugations upon the inner wall of said compartments.

14. A radio unit as in claim 10 having in addition corrugations upon the inner wall of said compartments.

15. A radio tube having an envelope, cathode, grid, and anode electrodes within said envelope, said envelope being of dielectric material, said anode being in contact with said envelope, a metallic insert on the inner surface of said envelope in contact with said anode, and a metallic conductor leading from said insert through the

wall of said envelope to the outside for the conduction of heat.
